UNITED STATES PATENT OFFICE.

MYRON J. CARPENTER, OF LA GRANGE, ILLINOIS.

TELEGRAPH SYSTEM.

No. 818,145.

Specification of Letters Patent.

Patented April 17, 1906.

Application filed June 2, 1905. Serial No. 263,877.

To all whom it may concern:

Be it known that I, MYRON J. CARPENTER, of La Grange, in the county of Cook and State of Illinois, have invented certain new and useful Improvements in Telegraph Systems; and I hereby declare that the following is a full, clear, and exact description thereof, reference being had to the accompanying drawings, which form part of this specification.

10 My invention relates to improvements in telegraph systems.

One of the objects of my invention is to provide a system of telegraphy in the practice of which signals at the receiving end become audible only to the receiving operator, thereby avoiding annoyance to other persons not inured to the noise produced by telegraph-sounders, and, furthermore, guarding against publicity by other operators over- 20 hearing and reading the signals, as when a sounder is used.

Another object of my invention is to provide a self-contained instrument to be used in connection with an ordinary telephone-line, by means of which Morse or other similar telegraph-signals may be transmitted over said lines, thereby converting the telephone system into a telegraph system and using the two systems conjointly and simultaneously.

30 Other objects will become apparent to those skilled in the art from the description hereinafter.

In the drawings, Figure 1 represents a telegraph and a telephone transmitter associated in operative relation as arranged in my system. Fig. 2 is a partly diagrammatic view of the instruments and circuits constituting a modified phase of my system.

The same reference characters are used to 40 indicate like parts in both of the views.

In Fig. 1 A is a support for the key K and the telephone-transmitter T and acts as a medium for communicating the mechanical vibrations produced by the operation of the 45 key to said transmitter. k is the lever of the telegraph-key, provided with a manipulating-button k'. The anvil k² of the key is adapted to receive the impact of the upper circuit-closing contact k³ of the key K. k⁴ is a metallic base upon which the key-lever k is supported. In Fig. 1 the telephone receiver and transmitter are arranged and adapted to be contained in the usual telephone-line circuit. The telegraph-key K, as shown in Fig. 1, is not 55 intended to be included in any electric circuit whatever. The mechanical vibrations pro-

duced by the manipulations of the key K are taken up and conducted to the telephone-transmitter by means of the intervening medium—the support A—and these vibrations 60 and those produced by the voice will be transmitted over the line quite independently of each other.

In Fig. 2 the telegraph-key is in the local electric circuit with the carbon contact portions of the transmitter T.

The transmitter T is fixed to the base A by means of the screws or bolts t⁴ and t⁵, respectively. An opening t⁶, which may be of the character usually employed for the reception 70 of the mouthpiece t⁸, is brought into actual contact with and closed by means of the base A, so as to shut out extraneous sounds, the transmitter thereby taking up solely the vibrations of the base A, produced by the mechanical manipulation of the key K. When the key K is included in the local circuit, as shown in Fig. 2, the mechanical vibrations produced by the manipulation of the key are transmitted through the medium of the base 80 A to the telephone-transmitter T and thereby to line just as they are when the local circuit is not opened and closed by the manipulation of the key, as in Fig. 1. The opening and closing of the primary circuit of the transmitter by the manipulation of the key produces electric impulses that intensify the effect produced by the mechanical operation of the key, and corresponding electric impulses are transmitted to line, thereby producing 90 clear and distinct telegraphic characters.

T' is an ordinary telephone-transmitter.

I is an induction-coil which may be used or not, as desired, having a primary circuit i and a secondary circuit i'.

95 R is the usual receiver in the secondary circuit.

B is a battery, the source of current for the primary circuit of the transmitter, and S is a switch provided with a switch-arm s, pivoted at s', and contacts s² and s³ for the transmitter T' and T, respectively.

100 As my system is shown in Fig. 2, the telegraph-key K is in the local electric circuit with the contacts of the transmitter T.

105 The circuit I will now trace as follows: from the battery B over the wire 4 to one terminal of the primary coil i, through the coil over the wire 5 to the screw t⁷ in the base of the key, from thence over the lever k to the screw k³, and thence to the anvil k² of the key through the bolt t⁶ to one contact of the

transmitter T, from thence over the wire 3 to the contact s^2 , through the switch-bar s, over the wire 3, back to the battery B, thus completing the circuit through the transmitter and through the telegraph-key. It is evident that when the telegraph-key is manipulated the transmitter T will take up the mechanical vibrations due to the manipulation of the key, and it will also produce a co-acting effect in the secondary circuit, due to the opening and closing of the primary circuit by means of the key. The secondary circuit includes the secondary induction-coil i^2 , the wire 6, including the receiver R, connected to the line-terminal 8, and the line-wire 7 to the terminal 9.

In Fig. 1 the transmitter is simply attached to the base A, upon which the key K is mounted. The manipulation of the key will produce mechanical vibrations that are imparted to the transmitter through the medium of the support A, which are transmitted over the line to a distant telephone-receiver, through which they may be heard. The signals mechanically produced by the telegraph-key of Fig. 1 may be distinctly heard in the telephone-receiver by persons using the line for telephone purposes; but they will not interfere with such conversation. The vibrations produced in this manner by means of the telegraph-key are not objectionable to parties conversing over the line and do not produce so harsh an effect as when the telegraph-key is contained in an electric circuit and the circuit is periodically broken thereby.

When the switch S occupies the position shown, the system will transmit only the mechanical and electrical vibrations due to the manipulation of the telegraph-key K, and any extraneous sounds will not affect the transmission thereof. The telegraph-signals pass over the line clear and undisturbed.

The switch S illustrates a means whereby an ordinary telephone-circuit may be readily adapted for use in conjunction with my instrument. The same switchboards and methods of switching the telephone-circuits may be retained in connection with my system.

In Fig. 1 the telegraph-key is not included in an electric circuit and its manipulations do not affect the local circuit, except through the instrumentality of the vibrations produced by its mechanical manipulation, which are transmitted through the medium of the part A, upon which the key and the transmitter are supported.

When it is desired to use the system entirely for transmitting the human voice, this can be done by means of the transmitter T. To bring it into operation, the switch-arm s is thrown into contact with the terminal s^3 , thereby quickly disconnecting the transmitter T and connecting the transmitter T' in circuit.

The same circuit by the use of my system, as illustrated in Fig. 1, may be employed to transmit the human voice and the telegraph characters simultaneously without any interference and quite independently. The telegraphic signals will not disturb or annoy the persons engaged in conversation, while they are clear and intelligible to the telegraphic receiving operator during the continuance of the conversation.

In hotel-lobbies, where there are usually a great many people congregated, my system is very desirable. By its use the information coming over the telegraph-wires cannot be surreptitiously obtained by eavesdropping telegraphers. In places where it is desirable to produce no appreciably audible sounds of the telegraphic characters by the sending operator's key, as in the system shown in Fig. 2, it may be adjusted so that it will be susceptible of the very slightest movement and the circuit may be varied or manipulated thereby instead of depending entirely upon the vibrations made by the mechanical operation of the key to be transmitted by the transmitter.

I have found in practice that the system as it is illustrated in Fig. 1 is entirely satisfactory, and sound-vibrations made by the mechanical operation of the key in making the telegraph-signals when the transmitter is connected upon the same base, so as to directly receive the vibrations made thereby, may be read at the distant end of the line by means of an ordinary telephone-receiver with as much clearness and ease as if a sounder were present at the receiving end.

Having thus described my invention, what I claim, and desire to secure by Letters Patent of the United States, is—

1. In a system of telegraphy, the combination of a telegraph-key, a telephone-transmitter, a support common to both adapted and arranged to communicate mechanically vibrations due to the manipulation of the telegraph-key to the telephone-transmitter, a source of electric current, and a circuit including said source of current, the key, and the transmitter in series, whereby said transmitter is responsive to the sound-vibrations and to the current variations produced by the manipulation of said key.

2. In a system of telegraphy, the combination of a telegraph-key, a telephone-transmitter, a support whereon said key and transmitter are arranged in common, said support closing the mouth of the transmitter, whereby said transmitter is made responsive only to vibrations produced by the manipulation of the key.

3. In a system of telegraphy, the combination of a telegraph-key, and a telephone-transmitter mounted upon a support common to both, and a closure for said transmitter, whereby said transmitter is made

responsive to vibrations produced only by the manipulation of the key.

4. In a system of telegraphy, the combination of a telegraph-key and a telephone transmitter mounted upon a support common to both, an induction-coil, a source of electric current and a circuit including said source, key, transmitter and the primary circuit of an induction-coil, said transmitter being responsive to the sound-vibrations and

to the current variations produced by the manipulation of the said key.

In testimony that I claim the foregoing as my own I affix my signature in presence of two witnesses.

MYRON J. CARPENTER.

In presence of—

FORÉE BAIN,
MARY F. ALLEN.
